UNITED STATES PATENT OFFICE

EINAR EROLA, OF SALEM, MASSACHUSETTS

WALL BOARD

Application filed March 10, 1927. Serial No. 174,230.

This invention relates to wallboard and fastening strips for the same, and more especially to improved means for fastening to a wall, gypsum plasterboard or wallboard the sides of which are ordinarily covered with heavy paper or cardboard. The principal object of the invention is to provide wallboard sheets having an edge recess, and means for so fastening such sheets that the joints between the sheets will be substantially smooth and flat without protruding ribs or other projections which are objectionable and unsightly in appearance, and that the wallboard will not be injured by the fastening means.

Preferred embodiments of the invention are illustrated in the accompanying drawings, in which:

Fig. 1 is a plan view of two sheets of gypsum wallboard secured in accordance with my invention;

Fig. 2 is a fragmentary enlarged section on the line 2—2 of Fig. 1;

Fig. 3 is a similar sectional view on the line 3—3 of Fig. 1;

Fig. 4 is a fragmentary plan view of a modified form of fastening strips; and

Fig. 5 is an enlarged section on the line 5—5 of Fig. 4.

The invention consists essentially in providing longitudinal slots at the outer corners of adjacent sheets or panels of the wallboard, and preferably then inserting a fastening strip or strips over said slots and nailing said strips to the wall or other support.

In the illustrations the wallboard may consist of the usual gypsum plaster 6 and the top and bottom cover sheets 7 and 8, respectively, of cardboard or other sheet material. In preparing these sheets for the attachment of my improved fastening strips, the gypsum plaster is cut away at the edge of the sheet immediately beneath the top strip 7 providing adjacent slots 9 and 10 at the meeting edges of adjacent sheets or panels.

In Figs. 1 to 3, the fastening means comprise a pair of similarly L-shaped metal strips 11 and 12, which are inserted between the sheets of wallboard so that the inner edge of each flanged strip extends almost to the wall 13, while the shorter outer flanges meet

the cardboard sheets over the slots or recesses 9 and 10, respectively. These strips are fastened to the wall by nails 14 driven between the adjacent strips. It will be noted that when the nails are driven sufficiently to secure these strips the said inner edges abut the wall, as at 15 and 16, so that excessive hammering will not damage the wallboard. The outer flanged ends and nail heads will, however, be disposed below the plane of the outer surface of sheets 7, thereby avoiding projections. The space between the strips 11 and 12 and the recesses above the flanges may be filled with hard plaster to provide a smooth finished surface.

In the optional construction shown in Figs. 4 and 5, a single, flat reinforcing strip 17 is provided to span the space between the adjacent wallboards, the sides of the strip lying upon the cover sheets 7 over the slots 9 and 10. Holes 18 may be provided for the nails 19 at suitable intervals.

By utilizing either of the above constructions a simple yet effective fastening is achieved without injury to the material constituting the wallboard and without unsightly projections. The nails may readily be driven and removed, if desired, and since they pass through a substantially open space between the panels the workman may see that the nails are driven into a firm support. This feature is particularly advantageous when the wallboard panels are to be nailed upon laths or spaced sheeting.

Although the foregoing description defines two particular forms of this invention, it is obvious that the details of construction of the devices described may be varied if desirable without departing from the spirit of the invention as defined in the following claims. The principal and essential feature of the invention is the provision of a recess in the edge of a sheet of wallboard, beneath the usual covering material, and secondarily of means for securing the said edge of the panel to a support by any desired sort of attachment which, when attached, will not project above the surface of the panel, and which will not damage the wallboard.

I claim:

1. Wallboard consisting of a layer of plaster and a cover layer of sheet material on one surface and having a longitudinal slot in an edge of the plaster immediately beneath the cover layer, whereby the margin of the cover layer may be depressed into said slot by fastening means for securing the wallboard to a support.
- 10 2. A wallboard panel consisting of a layer of gypsum plaster and a covering layer of sheet material on its outer surface, and having a relatively shallow elongate slot in the plaster layer immediately beneath an overlying margin of the covering layer, the cross-sectional dimension of said slot being at least equal to the thickness of said covering sheet, whereby the said overlying margin may be depressed into and retained within said slot
- 15 3. Wallboard comprising a board-like body of plaster-like composition, and a flexible cover sheet applied upon the outer surface of
- 20 said body, the edges of the cover sheet approximately registering with the edges of the body, there being a slot along one edge of the wallboard formed in the body portion immediately adjacent the cover sheet whereby
- 25 the margin of the flexible sheet overhangs said slot, and the slot being relatively shallow transversely of the board and sufficiently deep edgewise thereof to receive the overhanging sheet margin when the latter is de-
- 30 pressed into the slot by fastening devices for securing the wallboard to a support.

In testimony whereof I affix my signature.
EINAR EROLA.
